UNITED STATES PATENT OFFICE.

HERMAN MOON, OF GROVE CITY, PENNSYLVANIA, ASSIGNOR OF ONE-HALF TO W. M. DIGIT, OF GROVE CITY, PENNSYLVANIA.

WRENCH.

1,075,434.

Specification of Letters Patent.

Patented Oct. 14, 1913.

Application filed May 23, 1913. Serial No. 769,540.

To all whom it may concern:

Be it known that I, HERMAN MOON, a citizen of the United States, residing at Grove City, in the county of Mercer and State of Pennsylvania, have invented a new and useful Wrench, of which the following is a specification.

This invention relates to a wrench adapted to grip and obtain a purchase upon pipes 10 and similar structures.

An object of the present invention is to provide a wrench adapted to force the jaws thereof against the cylindrical surface with a large pressure to thereby more effectually 15 grip the sides of the cylindrical pipe.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, without 25 departing from the spirit of the invention.

In the drawings accompanying this specification and forming a part thereof, the preferable form of my invention is illustrated, in which:—

30 Figure 1 is a side view of my improved wrench. Fig. 2 is a side sectional view thereof, taken on the line A—A of Fig. 3. Fig. 3 is a bottom view of my improved wrench in which one of the jaws thereof has 35 been broken away to more clearly illustrate the construction of the jaw therebehind.

Referring to the drawings in which similar reference numerals designate corresponding parts throughout the several views, 1 is 40 the lever handle of the wrench which is adapted to be gripped and moved in the direction as indicated by the arrow in Fig. 2 during the using of the wrench. The lever handle 1 is provided with the cross bar 5 and the bifurcated head 2 extending therefrom. The bifurcated head is provided with the slotted apertures 3 therein and with the notches 4 at the outer periphery thereof. In order that the bifurcated head 5 portion 2 may be suitably strengthened, a cross brace rod 6 is provided and is secured to the portion 2 as more clearly illustrated in Fig. 3.

55 Mounted rotatably with respect to the lever 1 and head 2 are the plates 7 provided

at their front edges with the enlarged jaw portions 8 which portions preferably include an angle of 90 degrees therebetween. In some classes of work it has been found advisable to provide the said jaws with the 60 gripping members 9 hereinafter termed bits and in the present instance there has been illustrated one of the said bits as being formed with wedge-shaped ends which engage suitable undercut portions in the surface of the jaws. The rear portions of the plates 7 are provided with the reinforcing strip 10 which conforms to the curvature of the said plate and the periphery 12 thereof is the arc of a circle, the center of which 70 is located at 11. The plates 7 are provided with suitable apertures therein which are offset from the point 11 as more clearly illustrated in Figs. 1 and 2 and through which apertures extends the smaller portion 13 of 75 the pivot pin or bolt 14. The portion of the bolt 14 lying between the plates 7 is enlarged as more clearly illustrated in Fig. 3, by which a suitable shoulder is provided which serves to hold the plates 7 in spaced 80 relation and furthermore provides a transverse brace therefor. A suitable retaining nut 15 is used to grip the outer portion of the plates 7. By the positioning of the pivot pin 14 offset from the center of curvature 11 85 of the inner periphery 12 of the plates a cam-like action is obtained with respect to the cross bar 5 and the inner of the said plates. The cross bar 5 is adapted to contact with and bear against the inner periphery of the plate and inasmuch as the said inner periphery is or lies upon a curve 90 the center of which is at 11, as the cross bar 5 moves toward the ends of the arc the head portions 2 will be drawn inward and the bolt or pivot pin 14 will travel toward the inner end of the slotted apertures 3 in the head, the particular advantage of which will be hereinafter more fully described. In order to further strengthen and hold the 100 plates 7 in spaced relation, a suitable bolt 16 is placed near the upper edge of the plates 7 and is provided with the retaining or spacing block 17 and a suitable nut 18 the spacing block 17 and nut 18 coöperating to engage each side of the said plates and to thereby hold the same in fixed relation. The bolt 16 further provides a securing means to which the chain 19 is secured. The chain 19 is of the usual construction 110

such as is used in connection with wrenches of the character described, is adapted to embrace the cylindrical surface which the wrench is intended to grip and is provided 5 with the cross pin 20 secured to the end thereof. The said pin is of a size to fit securely in and engage the side walls of the notches 4 of the head portions 2.

The wrench described is simple in construction and possesses strength and rigidity 10 which is desirable in wrenches of this character.

In the practical use of my improved wrench the jaws 8 are positioned against the 15 cylindrical surfaces which in most cases will be a pipe and chain 19 wrapped therearound and the cross pin 20 positioned in one of the notches 4, it being understood that a plurality of these notches are to be provided in 20 order to adapt the wrench to pipes of varying sizes. With the pipe in contact with the jaws 8 and the chain 19 wrapped therearound with the cross pin 20 installed within a suitable notch, by a turning of the handle 25 as illustrated by the arrow in Fig. 2, the notches 4 will be turned about the pivot pin 14 as a center and the chain thereby tightened about the wrench which will force the said jaws into frictional engagement with the surface of the pipe. By reason of the 30 fact that the cross bar 5 and the inner peripheral surface 12 of the jaws are cam-like in action, the head portions 2 will be drawn inward and away from the jaws 8, by which 35 action the notches 4 will also be drawn inward, which will tend to give the final tightening to the chain about the pipe and will be equivalent to a lever of great length, which will tend to secure the jaws 8 against 40 the pipe surface with an enormous pressure and will insure a successful gripping thereof by means of the jaws.

Having thus fully described the construction and operation of my improved wrench, 45 what I claim to be new and original with me is:—

1. A wrench comprising a handle with a head portion, said head portion provided with a central slotted aperture and a plurality of peripheral notches, side plates 50 formed with jaws at the front ends thereof, bits secured to said jaws, a spacing bolt secured to the upper portion of said side plates, a chain secured thereto, a cross pin secured to 55 the free end of said chain adapted to fit within said notches.

2. A wrench comprising a handle, a bifurcated head portion therefor, said head portion provided with a slotted aperture there- 60 in and a plurality of peripheral notches, side plates formed with jaws at the front

end thereof, and a cam surface at the rear thereof, a cross bar secured to said handle adapted to contact with said cam-like surface of said side plates, a pivot pin extending between said side plates and through said slotted aperture, a chain secured to said plates, a cross pin secured to said chain adapted to engage in said notches. 65

3. A wrench comprising a handle, a cross bar at one end thereof, a head portion secured to said cross bar, said head portion provided with a slotted aperture and a plurality of peripheral notches therein, side plates formed with jaws at the front ends 70 thereof and a cam-like surface at the rear ends thereof, a pivot pin extending between said side plates and adapted to hold the same in spaced relation, said pivot pin extending through said slotted aperture, said rear cam 75 surface of said side plates adapted to contact with said handle cross bar, a chain secured to said side plates, a cross pin secured to the free end of said chain, adapted to engage said peripheral notches. 80

4. In a device of the class described, the combination of a handle, a cross bar at one end thereof, a bifurcated head portion secured to said cross bar, said head portion provided with a central slotted aperture and 90 a plurality of peripheral notches therein, side plates formed with jaws at the front ends thereof and a cam-like surface at the rear ends thereof, said cam-like surface adapted to contact with said handle cross bar, said side plates provided with a pivot pin extending therebetween adapted to hold the same in spaced relation, said pin extending within and slidably engaging the walls 95 of said slotted aperture, a spacing bolt secured to the upper extremity of said side plates, a chain secured to said spacing bolt, a cross pin secured to the free end of said chain adapted to engage said peripheral notches. 100

5. A wrench comprising a handle with a head, said head provided with outwardly extending shoulders, said head provided with slotted grooves therein, side plates including wrench jaws pivotally and slidably secured to the said head, said side plates provided with a cam-like surface contacting with the overhanging shoulders of said head, and a flexible element secured to said side plates and detachably secured to said head. 110

In testimony that I claim the foregoing as my own, I have hereto affixed my signature in the presence of two witnesses.

HERMAN MOON.
